DESIGN FOR A CAMERA HOLDER

Roy C. Swanson, St. Paul, Minn.

Application November 18, 1943, Serial No. 111,722

Term of patent 3½ years

(Cl. 61—1)

To all whom it may concern:

Be it known that I, Roy C. Swanson, a citizen of the United States, residing at St. Paul, county of Ramsey and State of Minnesota, have invented a new, original, and ornamental Design for a Camera Holder, of which the following is a specification, reference being had to the accompanying drawing, forming part thereof.

I claim:

The ornamental design for a camera holder, as shown.

ROY C. SWANSON.
